UNITED STATES PATENT OFFICE.

FREDERICK A. TAYLOR, OF KANSAS CITY, MISSOURI.

LATCH MECHANISM FOR SILO-DOORS.

1,340,922.

Specification of Letters Patent.

Patented May 25, 1920.

Application filed January 29, 1918. Serial No. 214,303.

To all whom it may concern:

Be it known that I, FREDERICK A. TAYLOR, a citizen of the United States, residing at Kansas City, in the county of Jackson and 5 State of Missouri, have invented certain new and useful Improvements in Latch Mechanism for Silo-Doors; and I do declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

My invention relates to silos and more particularly to an improved means for retaining the doors of a silo firmly and tightly in position; the principal object of the invention being to construct a cam-latch mechanism that may be adjustably fixed to a silo door, to compensate for irregularities or variations in thicknesses of mortar joints or materials of construction used in the silo 20 and so that proper connection with a coöperating anchor member may be made and whereby the door section to which the device is fixed may be drawn tightly to position to effect an air and weather proof joint. 25 It is a further object of the invention to so construct the devices that a part thereof may incidentally serve as ladder steps by which a person may gain access into the silo.

In accomplishing these objects I have provided improved details of structure the preferred forms of which are illustrated in the accompanying drawings, wherein:—

Figure I is a perspective view, showing a 40 portion of a silo, with door sections located and held therein by means of latch mechanism constructed according to the present invention.

Fig. II is a transverse, sectional view of 45 the same on a vertical line through the door sections.

Fig. III is a plan view of one of the latch devices particularly illustrating the step member.

Fig. IV is an enlarged front view of the same parts.

Referring more in detail to the drawings:—

1 designates a portion of a silo of certain 55 construction wherein door latches embodying the present invention are particularly

adapted for use; the silo here shown being of tile construction and provided at one side with a vertically extending opening 2 wherethrough ensilage may be delivered 60 into or discharged from the silo, and which is normally closed, to retain the ensilage, by a plurality of superimposed door sections 3.

Extending horizontally across the door opening 2 at regularly spaced and convenient 65 intervals, are tie rods 4, the opposite ends of which are embedded and anchored solidly in the silo wall so that the rods may serve to tie the sections of the silo wall at opposite sides of the opening substantially together. The bars serve also, as will later be described, as anchor members to which the door latches may be removably attached and on which the step forming portions of 70 the latches may be supported and retained 75 in functional position.

The sections 3, forming the door which closes the opening 2, are preferably of wooden construction and are slightly greater in width than the opening, and when 80 the doors are in functional position, their vertical edges are located in seats 5—5' at the inner faces of the walls at the opposite sides of the opening. At their upper and lower horizontal edges the doors are provided respectively with extending tongues 6 and 7 that respectively underlie and overlie similar tongues of adjacent sections to form a closed and effective joint. Each of 85 the sections is also provided on the outer side, along its vertical edges with packing 90 strips 8—8', of felt or the like, and on the outer face of the tongues 6 with similar strips 9 whereby, when the sections are properly located and latched in position, 95 weather tight joints are effected.

Fixed to each of the door sections 3 is a latch 10 constructed according to the present invention, whereby the sections may be drawn tightly against the wall-seats and locked in closed position. Each of the latches comprises a vertically adjustable bar 11, slidably mounted in spaced brackets or guide ways 12—12' that are attached to the section by bolts or other anchor members 100 13; the bars being provided at their upper ends with threaded shanks 14 and at the lower ends with a plurality of spaced apertures 15 for receiving cotter pins 16, whereby displacement of the bars from the guide- 110 ways is prevented.

Attached to the upper end of each of the

bars 11 is a horizontal latch plate 17, which incidentally forms a step, as before stated; the said plate being provided at its rear edge, with a centrally depending ear 18 having an aperture 19 therethrough for receiving the outwardly extending, threaded shank 14 at the upper end of the bar 11, the ear being retained by means of a nut 20 that is adjustable on the shank and is adapted to bear against the ear to effect an inward, or permit outward movement of the step or latch plate on the cross bar 4.

Depending centrally from the outer edge of the step plate are spaced wings 22-22', between which a cam lever 23 mounted on a cross pin 24 is pivotally mounted, the said lever comprising a cam head 25 adapted, when the free end of the lever is moved downwardly, to engage and tighten against the outer edge of the adjacent bar 4, to move the latch plate outwardly, and through its connection with the bar 11, tighten the door section to which the bar is attached, against the seats.

It is apparent that by providing the vertical adjustment of the bars 11 by the slideable mounting in the brackets 12-12', the latches may be moved vertically to permit proper attachment with the cross rods 4, and that by a proper adjustment of the nuts 20, inwardly or outwardly on the shanks 14, a desirable tightening effect of the door sections against their seats may be obtained.

With the devices so constructed and mounted on the door sections, in using the same, the bottom door is first located in proper position in the opening 2. The rod 11 fixed thereto is then moved vertically in the brackets 12-12' so that the latch plate 14 thereon will rest horizontally on the upper edge of a cross rod 4. With the step in this position the cam lever is moved downwardly to tighten the cam head against the bar 4 to draw the latch outwardly, which by its connection with the rod 11, draws the door section tightly against its seats; it being apparent that by proper adjustment of the nut 20 on the shank 14 any incidental variation in the location or spacing of the anchor bar may be met and a proper tension may be placed on the door.

After the first section is properly placed, ensilage is delivered into the silo up to the height of the section. Another section is then added and more ensilage delivered into the silo. This operation being repeated until the silo is filled.

To remove the sections, it is only necessary to loosen the cam lever from the bar 4 so that the latches may be freed therefrom and the door section moved inwardly from the opening.

It is apparent that by use of a latch of this character a substantial and effective device is provided for retaining the door sections in place. The device may also be easily applied and operated and not only provides means for holding the door sections in place but also serves effectively as a step for facilitating access to the silo.

Having thus described my invention, what I claim as new therein and desire to secure by Letters Patent, is:-

1. In combination, a silo provided with a door opening, a rod carried by the silo and extending across the door opening, a door, a vertical rod carried by the door and having a right angularly projecting end, a latch plate having a flange on its inner end through which the right angularly projecting end of the rod extends, means for securing the plate to the vertical rod, depending bearings on the under side of the plate, the first named rod being receivable between the bearings and the flange, and a cam journaled in the bearings for engagement with the last named rod.

2. The combination with a silo provided with a door opening and rods extending across the door opening, of a door member in the opening having a vertically adjustable rod provided with an outwardly projecting end, a horizontal plate having a depending flange engaging the outwardly projecting end of the rod, means for securing the flange to the rod, depending bearings carried by the plate, and a cam carried by the bearings for engagement with the rod extending across the door opening.

In testimony whereof I affix my signature.

FREDERICK A. TAYLOR.
